UNITED STATES PATENT OFFICE.

MAX DREGER, OF ESSEN-ON-THE-RUHR, GERMANY, ASSIGNOR TO FRIED. KRUPP AKTIENGESELLSCHAFT, OF ESSEN-ON-THE-RUHR, GERMANY.

SHRAPNEL.

932,004.

Specification of Letters Patent. Patented Aug. 24, 1909.

Application filed September 15, 1906. Serial No. 334,709.

To all whom it may concern:

Be it known that I, MAX DREGER, a subject of the Emperor of Germany, and a resident of Essen-on-the-Ruhr, Germany, have 5 invented certain new and useful Improvements in Shrapnels, of which the following is a specification.

The present invention relates to base chamber shrapnels, that is to say, those shrapnels 10 which have their charge arranged in the rear part of the projectile. In the known projectiles of this type, the impact fuse is arranged at the nose of the projectile and the charge consequently does not enter into 15 effect until some time after the impact, that is to say, the bursting of the charge may be delayed until the projectile has passed some distance behind the target.

The object of the present invention is to 20 improve the base chamber shrapnels with regard to their effect by impact in such a manner that the shrapnels enter into effect at the moment of impact and thereby become highly effective in lateral directions.

25 In the accompanying drawing one embodiment is shown in longitudinal section by way of example.

The bore of the projectile-body A is divided by the driving disk D into two chambers and is closed toward the front by a time-fuse B and toward the rear by a screw-plug C. In the front chamber, the charging shot E and the igniting tube F are located. In the rear chamber, which has strong walls, 30 is arranged the charge G which is a bursting charge of such a nature (such as smokeless powder) that it becomes detonated when sufficiently excited. An impact fuse H, which is secured in the screw-plug C, projects into 35 the charge G. The igniter h' of the impact fuse H is in connection with a detonator J which is separated from the charge G by a cap K. The detonator serves the purpose of effecting detonation of the charge G when 40 impact of the projectile takes place.

45 By reason of the above-described arrangement, the charge G is detonated immediately on impact of the projectile, that is to say, the

projectile-body bursts. At the moment of impact, the fragments of the projectile-body, 50 therefore, make the projectile highly effective in lateral directions. The projectile is, therefore, particularly useful against field guns provided with protecting shields. The action of the projectile under the effect of the 55 time fuse is apparent.

Having described my invention, what I claim as new is:

1. A shrapnel having a single base-chamber charge of an explosive substance capable 60 of both low and high explosive action; a time fuse causing the charge to explode during the flight of the shrapnel with low explosive action, and an impact fuse provided with a detonator and located in immediate 65 proximity of the charge, said impact fuse causing the charge to detonate on impact of the shrapnel, with high explosive action.

2. A base chamber shrapnel having a single charge of an explosive substance capable of 70 both low and high explosive action; a time fuse communicating with the charge to cause the charge to explode during the flight of the shrapnel to act as a shrapnel charge; and an impact fuse located in immediate proximity 75 of the charge and causing the charge to detonate on impact to act as a grenade charge.

3. A base chamber shrapnel having a single charge of an explosive substance capable of 80 both low and high pressure action, said charge being located in the base chamber of the shrapnel; a time fuse communicating with the charge to cause the charge to explode during the flight of the shrapnel to act as a shrapnel charge; and an impact fuse 85 provided with a detonator and located within the charge; said impact fuse causing the charge to detonate on impact of the shrapnel to act as a grenade charge.

The foregoing specification signed at Dus- 90 seldorf, Germany, this 11th day of August, 1906.

MAX DREGER.

In presence of—
WILLIAM ESSENWEIN,
ALFRED POHLMAYER.
